UNITED STATES PATENT OFFICE.

JAMES S. BAKER, OF ALTOONA, PENNSYLVANIA, ASSIGNOR OF ONE-HALF TO HARRY G. GRAZIER, OF ALTOONA, PENNSYLVANIA.

RAILWAY BRAKE-SHOE.

No. 896,076.

Specification of Letters Patent.

Patented Aug. 18, 1908.

Application filed January 11, 1908. Serial No. 410,899.

To all whom it may concern:

Be it known that I, JAMES S. BAKER, a citizen of the United States, residing at Altoona, in the county of Blair and State of Pennsylvania, have invented certain new and useful Improvements in Railway Brake-Shoes, of which the following is a specification.

This invention relates to railway brakes, and has particular reference to the provision of a brake shoe for railway cars, the construction being such that all danger of breakage of the shoe or the same becoming detached from the brake beam, tending to cause derailment of the train, will be reduced to the minimum.

More definitely speaking, the invention comprises a brake shoe made up principally of a cast metal body portion of substantially uniform thickness and curved to conform with the curvature of the wheel with which it is intended to coöperate, a tough metal plate back for the body portion, of peculiar form, and a novel construction of attachment means whereby the brake shoe is secured to the brake beam.

The mechanism whereby the objects of the present invention are attained will be better understood as this description progresses, and to this purpose reference is to be had to the accompanying drawings in which,

Figure 1 is a general perspective of a brake shoe made in accordance with the present invention, portions being broken away; Fig. 2 is a central transverse section, and Fig. 3 is a fragmentary longitudinal section on the line x—x of Fig. 2.

Throughout the following description and on the several figures of the drawings, like parts are referred to by like reference characters.

The brake shoe made in accordance with this invention may be of any preferred size or dimensions, preferably in accordance with the M. C. B. standard, and comprises a heavy body portion 10, preferably made of cast metal. In order to strengthen said body 10 and to provide a means whereby said body may be secured to the brake beam and there held until substantially entirely worn out without any danger of breaking or dropping to the rail, I provide a tough steel plate 11 for the said body, the said plate being provided with a slot 12 intermediate of its ends

and the ends being bifurcated for the purpose to be presently set forth. On opposite sides of the slot the steel plate is struck up to form sockets 13. The total width of the plate is slightly less than the width of the body 10, and the length of the plate is 60 slightly less than the length of the body.

A U-shaped attachment loop 14 having legs 15 and outwardly projecting feet 16 constitutes the immediate means for attachment of the brake shoe to the brake beam. The feet 16 are received in the aforesaid sockets 13 and lie between the steel plate and the body portion and the bottoms of the feet lie substantially flush with the inner face of the said plate 11. It will be seen therefore that the inner face of the feet and plate lie substantially parallel with the inner face of the body 10, and for this reason the body 10 may be practically entirely worn away before any part thereof will be allowed to drop from its fastenings.

In constructing the brake shoe as herein set forth, the loop and plate are properly assembled and placed in a suitable mold after which the body portion is cast thereupon, portions of the metal of the body passing through the slot 12 and bifurcations of the ends of the plate whereby the ends of the plate are embraced by the cast metal, the sockets 13 and feet 16 are embedded in cast metal, and the legs 15 of the loop are substantially embraced by the same, whereby the loop 14 is not only permanently secured in place by means of the said sockets but is prevented from distortion or rupture by the heavy body of metal wherein it is embedded.

While I have herein set forth the best manner of construction of the brake shoe for all practical purposes, it is to be understood that the specific details of construction may be varied in certain minor particulars so long as the spirit of the invention is not departed from.

I claim:

1. A railway brake shoe comprising a cast metal body, a steel strengthening plate secured to the back of said body, the ends of the steel plate terminating slightly short of the ends of the body and an intermediate portion thereof being slotted and struck up to form sockets on opposite sides of the slot, and a U-shaped attachment loop having feet received in said sockets, portions of the metal

of the body extending over the ends of the plate and through the slot to embrace said feet and sockets.

2. In a railway brake shoe, the combination of a cast metal body, a steel plate back therefor having a central slot and bifurcated ends, the plate on opposite sides of the slot being struck up to form sockets, and a U-shaped attachment loop having feet fitted 10 within said sockets, the metal of the body ex-

tending through the slot and bifurcations to cover said feet and sockets and to embrace the ends of the back.

In testimony whereof I affix my signature in presence of two witnesses.

JAMES S. BAKER.
